FIG. 5

FIG. 7

FIG. 8

FIG. 9

FIG. 1 is a perspective view of a filing unit embodying the design of this invention;

FIG. 2 is a front elevational view of the filing unit;

FIG. 3 is an end elevational view of the filing unit;

FIG. 4 is a rear elevational view of the filing unit;

FIG. 5 is a top plan view of the filing unit;

FIG. 6 is a cross-sectional view taken along plane VI—VI of FIG. 2;

FIG. 7 is a perspective view of an alternative embodiment filing unit embodying the design of the invention;

FIG. 8 is a perspective view of an alternative embodiment filing unit embodying the design of the invention; and

FIG. 9 is a perspective view of an alternative embodiment filing unit embodying the design of the invention.

I claim:

The ornamental design for a filing unit, substantially as shown.
